APPARATUS AND PROCESS FOR FLUIDIFYING AND MIXING BY MEANS OF COMPRESSED AIR

Alexander Hasselbach, Dessau, Germany, assignor to G. Polysius Aktiengesellschaft, Dessau, Germany

Application April 18, 1939, Serial No. 268,582
In Germany December 30, 1935

4 Claims.

(CL 259—4)

This invention relates to processes of mixing bulky pulverulent materials, such as cement raw materials, coal dust, flour, and the like, and to apparatus for effecting such processes. Among the objects of the invention are the reduction of the time and expense required for mixing large masses of such materials, and an increase of efficiency whereby a more completely homogeneous mass may be obtained than by prior methods of mixing.

The application is a continuation in part of my prior application Serial No. 118,027, filed December 28, 1936, wherein is disclosed a method of mixing which involves discharging the material into a mixing bin or tank while simultaneously introducing a limited quantity of air under pressure into the material, and subsequently intensively mixing the material by the introduction therein of much larger quantities of air under pressure. By introducing a relatively small quantity of air into the material during the filling period, I am enabled to cushion the fall of the material into the tank so as to prevent the packing which would otherwise inevitably occur, the subsequent intensive mixing of the material being thereby facilitated. I have found that this treatment of the material during the filling of the tank results in the establishment of a substantially fluid condition, the air thus introduced suffusing the material so that the mass is of relatively low density; this aeration of the material effectively prevents the formation of a dense mass which would otherwise result from the discharge of the material into the tank. Consequently, when the filling is completed, the mixing may be promptly and efficiently initiated, and the larger quantities of air then introduced create a state of turbulence, the material boiling violently in much the same manner as a liquid subjected to excessive heating, with the result that complete mixing can be rapidly effected.

Not only is the efficiency of the mixing operation improved materially by this procedure and the time required for mixing decidedly shortened, but there is a very substantial saving effected in the amount of compressed air required by reason of the fact that the larger quantities of air are introduced only after the filling is completed and are immediately effective in creating the desired turbulent condition owing to the absence of densely packed material.

The process is preferably carried out by introducing the air in an extremely fine state of division, such as may be established by forcing the air through porous stone or the like. I have found, however, that for effective mixing by finely divided air particles it is essential that the air be admitted into the tank over a rather large area, a very considerable volume of air being required if the desired condition of turbulence is to

be imparted to the material. Thus, if the tank is of cylindrical shape, air should be admitted over substantially the entire area of the bottom of the tank; if the tank is of varying horizontal sectional area, the area of air admission should be comparable to the mean horizontal sectional area of the tank.

One form of apparatus for carrying out the process is illustrated in the accompanying drawings, in which:

Figure 1 is a horizontal sectional view of a tank or silo provided with suitable devices for admitting air or other gaseous medium under pressure and in finely divided form;

Figure 2 is a vertical sectional view of the tank shown in Figure 1;

Figure 3 is a plan view of a preferred form of air admitting unit;

Figure 4 is an elevation, partly in section of the structure shown in Figure 3;

Figures 5 and 6 are transverse sectional views taken on the lines 5—5 and 6—6 respectively of Figure 3; and

Figure 7 is an enlarged fragmentary sectional view of the air inlet for the unit shown in Figure 3.

For convenience in describing the invention, reference is made to the preferred form of apparatus illustrated in the drawings and specific language is employed to describe the same. It will nevertheless be understood that variation of this structure within reasonable limits is contemplated and that the invention includes within its scope such alterations and modifications of the structure described herein as would occur to one skilled in the art to which the invention relates.

In Figure 1 is illustrated the lower end of a tank or silo of generally cylindrical shape, the peripheral wall of the tank being indicated at 10. Substantially the entire bottom wall 15 of the tank is covered by a plurality of individually formed devices 11, the major portion of the upper surface of each of which, indicated at 12, is of porous material and forms a support for the material to be mixed. Each of the devices 11 is supplied with air or other gaseous medium under pressure from a main supply conduit 13 through a plurality of smaller pipes 14, the arrangement being such that the gaseous medium is forced upwardly through the porous surface to suffuse the material supported thereon. The material to be mixed is introduced into the upper portion of the tank through a supply conduit 18, a vent 19 being provided to permit discharge of excess gaseous medium from the tank. The devices 11 are so arranged as to leave uncovered a plurality of outlets 20 in the bottom wall 15 of the tank, four such outlets being illustrated in Figure 1. Associated with these outlets are discharge conduits 22 which deliver the material into a single large

conduit 23, the withdrawal of material being controlled by a valve 24 in the latter.

Each of the devices 11 is preferably constructed as shown more particularly in Figures 3-7 inclusive, and includes a generally dish-shaped rectangular member 26, preferably cast of metal. This casting is formed to provide inwardly directed horizontal flanges 27 about the periphery thereof, on which are received flat plates 28 of porous material, such as porous stone, porous caoutchouc or the like. The upper peripheral edges of the casting are turned inwardly as indicated at 29 and metal of a low melting point, cement or the like, indicated at 30, is poured in position beneath these flanges and about the periphery of the plates 28 to secure the latter in position. Laterally extending strengthening ribs 32 cooperate with the peripheral and bottom walls of the casting 26 to define closed spaces 34 lying beneath the plates 28, and extending within these enclosed spaces and longitudinally of the casting 26 are extensions 36 of the pipes 14, these extensions being perforated at spaced points. The point of entrance of the pipes 14 into the castings 26 may be sealed by packing as indicated at 37. The castings are provided with openings 31 extending therethrough by means of which they may be bolted or otherwise secured in position.

When a gaseous medium under pressure is supplied to the system of pipes 14, the medium will be uniformly distributed within the closed spaces immediately below the porous plates 28, and will be forced upwardly through the latter. Owing to the fact that practically the entire bottom of the tank is covered and constituted by these porous plates 28, a very substantial volume of air, in extremely divided form, may be introduced into the lower end of the tank in this manner.

It will be understood that the system of pipes 14 is so controlled by suitable valves that during the introduction of the materials to be mixed into the upper end of the tank, air is admitted through a limited number only of the plates 28, a sufficient quantity of air being thus introduced to maintain the materials in a light and substantially fluid condition so as to prevent packing as the result of the fall thereof through the entire length of the tank. When the tank has been filled, it is preferred that air shall then be admitted over substantially the entire area of the bottom of the tank, and the material having already acquired a generally fluid state, the quantity of air thus admitted is sufficient to agitate the material violently, a condition approximating the boiling of the liquid being maintained until the mixing is completed.

Obviously a similar result can be achieved by admitting, for the purpose of fluidifying the material, a relatively small amount of air under pressure through all or a major portion of the porous plates, the supply pipes for the same being suitably throttled to materially reduce the flow. The flow is thereafter increased by opening the control valves to effect thorough mixing of the material.

It will be appreciated that by the use of individual air admitting units, such as those illustrated herein, the expense of installation may be materially reduced, replacement simplified, and accurate measured regulation of the amount of air admitted may be readily effected.

As a modification of the process of mixing outlined herein, it is further proposed to admit air under pressure over a portion only of the bottom of the tank after the filling has been completed, so that less agitation is effected than is required for complete and intimate mixing. When the tank is to be discharged, and during discharge of the material therefrom, the maximum quantity of air is admitted. By such a method of operation it is possible to maintain the material in a substantially fluid condition during admission thereof to the tank, to mix the material to a limited extent after the tank has been filled, and to complete the mixing during the period of the discharge of the material.

It is found that such procedure affords very efficient final mixing of the materials and is extremely economical since the maximum amount of air is not admitted until the operation is substantially completed and the material is ready for delivery from the tank. Stratification of the material in layers of different density, or of different chemical or physical properties, is effectively avoided by this method.

Having thus described the invention, what is claimed as new and desired to be secured by Letters Patent is:

1. A structural unit for use in the formation of gas pervious walls for the suffusion of pulverulent materials with gas, said unit including a generally flat, dished member formed of material substantially impervious to gas, a generally flat element formed of porous material pervious to gas received within and serving as a closure member for said dished member, and means including a pipe extending within said dished member and having perforations at longitudinally spaced points for introducing gas under pressure in the latter.

2. In a process of fluidifying and mixing farinaceous or powdered bulky materials by means of compressed air, the successive steps of delivering the material to a container and maintaining the material thus delivered in a condition of substantial fluidity by simultaneously introducing therein a relatively small quantity of compressed air, and subsequently introducing a greater quantity of compressed air to stir and mix the material after filling of the container.

3. In a process of fluidifying and mixing farinaceous or powdered bulky materials by means of gas under pressure, the successive steps of delivering the material to a container and maintaining the material thus delivered in a condition of substantial fluidity by simultaneously introducing therein a relatively small quantity of gas in a finely divided state, and subsequently introducing a greater quantity of gas in a finely divided state to stir and mix the material after filling of the container.

4. In a process of fluidifying and mixing farinaceous or powdered bulky materials by means of gas under pressure, the successive steps of delivering the material to a container and suffusing the materials thus delivered with compressed gas in a finely divided state and in quantity sufficient to effect preliminary mixing of the materials, subsequently discharging the materials from the container and simultaneously suffusing the materials with a substantially greater quantity of the finely divided gas to complete the mixing.

ALEXANDER HASSELBACH.
